US00D913045S

(12) **United States Design Patent** (10) **Patent No.:** **US D913,045 S**
(45) **Date of Patent:** **** Mar. 16, 2021**

(54) **CONTAINER BASE**

(71) Applicant: **THE DECOR CORPORATION PTY LTD**, Scoresby (AU)

(72) Inventor: **Jim Samartgis**, Scoresby (AU)

(73) Assignee: **The Decor Corporation Ltd Pty**, Scoresby (AU)

(**) Term: **15 Years**

(21) Appl. No.: **29/609,350**

(22) Filed: **Jun. 29, 2017**

(30) **Foreign Application Priority Data**

Feb. 9, 2017 (AU) 201710739

(51) LOC (13) Cl. **07-07**

(52) U.S. Cl. **D7/602**

(57) **CLAIM**

The ornamental design for a container base, as shown and described.

DESCRIPTION

FIG. 1 is a top, front perspective view of a container base showing my new design;

FIG. 2 is a bottom, rear perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof; and,

FIG. 8 is a right side elevational view thereof.

The broken lines shown in the drawings represent portions of the container base and form no part of the claimed design.

1 Claim, 8 Drawing Sheets
